(57) **CLAIM**

The ornamental design for a power inverter, as shown and described.

DESCRIPTION

FIG. 1 is a top view of the power inverter according to the present invention.

FIG. 2 is a bottom view of the power inverter of FIG. 1.

FIG. 3 is a front view of the power inverter of FIG. 1.

FIG. 4 is a back view of the power inverter of FIG. 1.

FIG. 5 is a left side view of the power inverter of FIG. 1.

FIG. 6 is a right side view of the power inverter of FIG. 1; and,

FIG. 7 is a perspective view of the power inverter of FIG. 1. The broken line showing of the environment is for illustrative purposes only and forms no part of the claimed design.
